[57] CLAIM

The ornamental design for a carrier case blank, substantially as shown and described.

DESCRIPTION

FIG. 1 is a top plan view of a carrier case blank embodying my new design, the bottom plan view being a mirror image thereof.

FIG. 2 is a side elevational view of the carrier case blank taken along line 2—2 of FIG. 1.

The carrier case blank is constructed of material of conventional thickness, and the dashed lines in the drawing represent score lines.
